PRINTING TELEGRAPH APPARATUS

Donald P. Needham and Jacques Stussi, Chicago,
Ill., assignors to Teletype Corporation, Chicago,
Ill., a corporation of Delaware

Application July 17, 1940, Serial No. 345,906

2 Claims. (Cl. 197—149)

1

This invention relates to printing telegraph apparatus and more particularly to platen arrangements therefor.

The principal object of the present invention is to provide a mechanism for adjusting the operative relationship between a platen and the printing elements of a printing apparatus.

Specifically, the aligning mechanism according to the present invention is especially adapted for use with a disc type platen which is movable across the page for line printing, the page material remaining stationary in the character spacing direction. In the embodiment of the invention herein disclosed, the platen is described as employed with a page printer of the type shown in U. S. Patent No. 1,904,164, which in turn is used in a projection system of the type shown in copending application Serial No. 346,004, filed July 17, 1940, by W. J. Zenner.

The foregoing and other objects of the invention will appear from the following detailed description taken in conjunction with the accompanying drawings, in which,

Fig. 1 is a side view and partial section of the printer-projector mechanism shown in the aforementioned co-pending application;

Fig. 2 is an enlarged cross-sectional view of the printer platen and platen frame;

Fig. 3 is a view taken substantially on the line 3—3 of Fig. 2;

Fig. 4 is a top view of the part of the printer mechanism shown in Figs. 2 and 3; and

Fig. 5 is an enlarged side view of a type bar head.

Having reference to Fig. 1, a page printer of the type shown in U. S. Patent No. 1,904,164, and indicated generally as 11, has been modified in certain respects to adapt it for use with the projector system shown in the aforementioned copending application. The page printer 11 comprises side frame 12 and 13 to which is pivoted at 14 a platen frame, indicated generally as 15. The usual cylindrical form of platen has been dispensed with in the present embodiment of the invention and has been substituted by the disc form of platen 16, to which the present invention is particularly adapted.

To provide a running account of the message printed on the page material, a delivery mechanism is provided which comprises a means for permitting the record material to escape from the supply roll, and a web pulling means whereby the page material is advanced through the printing zone. The page material 17, in being delivered from the roll 18, is directed over a slack

2

bar 19, which is pivoted at 21 and normally biased clockwise by a spring 22, to maintain the page material stretched taut between the roller 19 and a flanged cylindrical guide 23, which is carried on a shaft 24 journaled in the plates 25 depending from side frames 12 and 13. The strip 17 is then directed over a roller 26 to which is fixed a ratchet wheel 27, the ratchet wheel and roller being carried on a shaft 28 journaled in the plates 25. Cooperating with the roller 26 is a pressure roller 29 which is carried on a standard 31 secured to a rock shaft 32. Pressure roller 29 is drawn into pressing relation with roller 26 by means of a spring 33. Associated with ratchet 27 is a pawl (not shown) which is connected to the web controlling mechanism of the printer 11 as described in the aforementioned patent.

Thus, in response to a predetermined selection, a function lever similar to function lever 34 is selected to raise the forward end of a push bar similar to push bar 35 upwardly into the path of the function bail blade 36. Then, when the push rod (similar to push rod 35) of the web controlling mechanism is actuated leftwardly by the function bail 91, the pawl associated with the ratchet 27 is actuated in such a manner as to impart clockwise rotation to the ratchet 27. In this manner, the ratchet wheel 27 is rotated clockwise one step which, through the cooperation of pressure rollers 26 and 29, acts in cooperation with the web pulling mechanism to deliver a predetermined amount of record material from the supply roll 18.

The record material 17, as it is delivered from the supply roll 18, is brought to the printing position by means of a web pulling or drawing mechanism, indicated generally as 37. The record material 17 as it leaves roller 26 is directed around guide rods 38, 39, and 41. These guide rods may take the form of a fixed rod, carrying guide rollers to eliminate friction. From the guide rod 41 the record material 17 is directed vertically through the printing zone and projection field to a guide rod 42 carried by a U-shaped shifting frame member 43 pivotally carried on pivot 44, which is suitably journaled in the frame of the projection apparatus. The page material 17 is then directed around a guide rod 45 carried in support 46 depending from bars 47 secured to angle iron cross bars 48 and 49 of the projection frame. From thence, the page material 17 is directed around a spindle 51 fixed to a shaft 52 journaled in standards 53 supported on said bars 44.

The shaft 52 is interconnected through a fric-

tion clutch (not shown) with a pulley 54. Continuous counterclockwise rotation is imparted to pulley 54 through the instrumentality of a belt 55 connected to a pulley 56 operatively carried on the main operating shaft 57 of the page printing apparatus. The shaft 57 is driven by a motor (not shown) which, through belt 55 and pulley 54, imparts a constant torque (through a friction clutch on shaft 52) to the spindle 51.

With this arrangement, the page material 17 is maintained in a taut condition between the spindle 51 and the roller 26. Thus, when the ratchet 27 is rotated one step, through the instrumentality of the web controlling mechanism of the printer, a predetermined amount of the page material 17 is delivered from the supply roll 18, which material is immediately taken up by the spindle 51 to preserve the taut condition of the page material.

As disclosed in the aforementioned Patent No. 1,904,164, the page printer 11 is controlled telegraphically by a selector magnet 61, which is connected in a signal line (not shown) on which are impressed code combinations of signaling impulses. The code signals control, through a sword and T-type selector (not here shown, but illustrated and described in said patent), a series of selector vanes 62, which in turn controls, through a series of bell cranks 60, a set of curved code bars 63. Code bars 63 and bell cranks 60 are supported on a movable type carriage, indicated generally by the numeral 64, which is provided with rollers 65 and 66, whereby it is adapted to travel on tracks 67 and 68, respectively, positioned between the side frames 12 and 13. Cooperating with code bars 63 are a plurality of pull bars 69 having individual springs 71. Code bars 69 are operatively connected by rack and pinion connections to a corresponding plurality of type bars 72 pivoted on a shaft 73.

Type carriage 64 is also provided with a spacing rack 74 which cooperates with a spacing mechanism (not shown), similar to that illustrated in Patent No. 1,904,164, to control the movement of type carriage 64 to form character spaces, tending in this movement to wind up a carriage return spring mechanism (not shown). Upon receipt of the carriage return signal, the carriage 64 is permitted, due to the energy stored in the carriage return spring, to return the type carriage 64 to its normal or beginning-of-line position, in a well-known manner. A pull bar bail 75 is mounted in the type carriage 64 and is provided with a roller 76 carried on a stud 77 on the bottom side thereof. Roller 76 operates between a pair of blades 78 and 79 of the main printing bail 81 so that bail 75 can be reciprocated by bail 81 in any position of the type carriage 64 during the printing of the line. Fastened to the printing bail 81 is one end of a printing spring 82, the other end of which is connected to a printing blow adjustment means, as shown in Patent No. 1,904,164. Bail 81 is mounted on a shaft 83 on which is also carried a printing bail actuator 84 which cooperates with a printing cam 85. Actuator 84 carries at the end of its upper arm a stud 86 which has abutting relation only with printing bail 81 and is not permanently connected thereto, the purpose of which, as will hereinafter appear, is to permit spring printing. Printing bail 81 is also provided with a pair of arms 87 which carry a bail 88.

Also carried on shaft 83 is a function bail comprising arms 89 and 91. Arm 89 is provided with a follower roller which cooperates with a function

bail cam 92, and arm 91 carries on its end the function bail blade 36.

Associated with the selector vanes 62 are a plurality of function levers 34 which are mounted on a pivot rod 93 and are provided with individual springs 94 which tend to rotate the function levers 34 clockwise into registry with the selector vanes 62. The function levers 34 are normally held out of engagement with the selector vanes 62 by means of the rod 88 of the function lever

10 bail. As previously mentioned, the platen frame 15 is pivotally supported on pivot 14 in the side frames 12 and 13. The platen 16 comprises a circular disc which is rotatably mounted on a carriage 95, which is slidable on rods 96 and 97 carried by the platen frame 15. Platen carriage 95 is connected to the type carriage 64, as will be presently described, so as to be movable therewith, the effective printing edge of the platen 16 being located coincident with the printing point or zone determined by the path of operation of the type bar 72. As will also presently appear, an adjusting means is provided to vary the distance 15 between the periphery of the platen 16 and the printing material 17, as well as to align the printing point properly and accurately with the type faces.

The platen frame 15 is adapted to be rocked from the "letters" or unshift position to the "figures" or shift position in the manner fully set forth in the aforementioned Patent No. 1,904,164. Briefly, the side frame of the platen frame 15 is provided with a lug 101 which operates between two adjustable stops 102 and 103. Adjacent to lug 101 there is pivoted to the side frame of the platen frame 15 on pivot 104 (Fig. 1), the upper end of a link 105, the lower end of which is pivoted to the horizontal arm of a bell crank lever 106 pivotally mounted at 107. To the lower end of the depending arm of bell crank 106 is connected a push bar 35, the free end of which overlies a leftwardly directed arm of the function lever 34. Push bar 35 is also provided with a shoulder 108 which cooperates with the function bail blade 36.

The platen frame 15 and platen 16 are shown in the "letters" or unshift position in Figs. 1 and 2 with the stop lug 101 against the upper stop screw 102. This condition is achieved when the function bail blade 36 has operated upon the shoulder 108 to move the push bar 35 leftwardly to rotate the bell crank 106 clockwise, thus raising the link 105 to cause the platen frame 15 to rock clockwise. A similar construction is provided for the "figures" or unshift mechanism. That is, an unshift function lever (similar to lever 34) is provided which, when selected, is caused to rotate clockwise to bring its rearwardly extending arm into operation to raise a push bar, similar to bar 35, into the path of the function bail blade 36 which, when it is permitted to operate leftwardly, will cause bell crank 106 to pull down link 105 to rock the platen frame 15 counterclockwise to bring its stop 101 against the lower stop screw 103. The platen frame 15 is maintained in its shift or unshift position by a spring actuated detent member 109 acting on a detent roller 111.

In Figs. 2, 3, and 4 is illustrated the manner in which the platen carriage 95 is connected to the type carriage 64 so as to be movable therewith. As previously mentioned, the platen carriage 95 is slidably supported on rods 96 and 97. Carriage 95 is provided with an eccentric stud 112 which

is engaged by the forked end of a bar 113, the left end of which is secured to a member 114, which in turn is secured by screws 115 to the type carriage 64. As viewed in Fig. 4, the circular platen 16 is rotatably mounted on the platen carriage 95 by means of an eccentric means 116. By means of the adjustment 116, the platen 16 is adjustable toward and away from the record material 17 to vary the clearance therebetween. To compensate for the effect of this adjustment upon the correct operative relationship between the platen and the type faces, rightward and leftward adjustment is also provided for the platen 16 through the instrumentality of the eccentric adjusting means 112 and 113. By means of the eccentric adjusting element 112 the correct alignment of the printing point of the platen 16 with the type faces 196 and 197 can be established.

The platen 16 is so positioned as to reduce to a minimum the obstruction of the projected image by the platen. To achieve this result the platen 16 is tilted with respect to the record material 17 sufficiently to clear the light cone. The peripheral surface of the platen 16, upon which printing is effected is slightly beveled so that in one of the shift positions of the platen the peripheral surface of the platen will be parallel to the record material. In the present embodiment of the invention, the peripheral surface of the platen 16 is parallel to the record strip when the platen frame 15 has been shifted to the upper case position, as indicated in Fig. 2 by the dotted line 117 of the platen 16.

To compensate for this arrangement of the platen 16, the type faces 196 and 197 on the type bar 149 are arranged as shown in Fig. 5. Moreover, this arrangement of type faces in cooperation with a shield 118 serves to prevent smudging during the printing operation. The shield 118 is vibrated into operative position in accordance with the shift position of the platen 16 by the ribbon vibrating lever 119 in the manner shown in the aforementioned copending application.

Associated with the platen 16 is a platen rotator 121 for automatically changing the printing point of the platen 16 in response to each carriage return operation. In response to a carriage return signal the carriage 64 and platen 95 are returned quickly to the beginning-of-line position, whereupon the platen 16 slides and rolls on the rotator 121 so as to change the printing point. In other words, through the instrumentality of the platen rotator 121 the platen 16 is controlled in such manner as to reduce to a minimum the number of times any particular print-

ing point on the platen is impinged upon, thereby reducing to a minimum the wear at a given point and thus prolonging the life of a platen.

It is, of course, understood that it is intended to cover not only the specific embodiment herein disclosed, but also such changes or modifications as come within the spirit of the invention and scope of the following claims.

What is claimed is:

1. In combination, a printing device having a carriage movable to form character spaces, said carriage supporting a plurality of pivoted type bars movable in printing toward a common locus, guide rails disposed in the direction of movement of said carriage, a platen carrier slidably supported on said guide rails, a rotatable platen mounted on said carrier, said platen comprising an inverted conical frustum, said frustum tiltably positioned so that its peripheral surface adjacent said common locus is in a vertical plane, means for connecting said carriage with said platen carrier, eccentric means for varying the spacial relationship between said peripheral surface and a predetermined vertical plane, and eccentric means operative at the point of articulation between said platen carrier and said carriage and effective as a consequence of the operation of said first mentioned eccentric means for effectuating a realignment between said common locus and said peripheral edge, whereby proper coincident printing relationship between said type bars and said platen is reestablished.
2. In combination, a printing device having a carriage movable to form character spaces, said carriage supporting a plurality of pivoted type bars moving in printing toward a common locus, guide rails disposed in the direction of movement of said carriage, a platen carrier slidably supported on said guide rails, a rotatable platen mounted on said carrier, said platen comprising an inverted conical frustum, said frustum tiltably positioned so that its peripheral surface adjacent said common locus is in a vertical plane, means for connecting said carriage with said platen carrier, eccentric means for varying the instant of impingement of said type bars on said surface, and eccentric means operative at the point of articulation between said platen carrier and said carriage and effective as a consequence of the operation of said first mentioned eccentric means for effectuating a realignment between said common locus and said peripheral edge, whereby proper impinging relationship between said type bars and said platen is reestablished.

DONALD P. NEEDHAM,
JACQUES STUSSI.
